PICKING MOTION FOR LOOMS

John Heaton, Riddlesden, Keighley, England, assignor to Electro-Pneumatic Looms Limited, Bradford, England, a British company

Application November 26, 1945, Serial No. 630,892
In Great Britain January 10, 1945

6 Claims. (Cl. 139—144)

1

This invention relates to the picking motion of looms whether of the single or multi-shuttle box type.

The accepted form of picking motion now in use includes the use of mechanism wherein picking arms or sticks are tied by straps to pickers which are caused to strike the shuttle and thus drive it across the loom on the sley. This arrangement although universal has several disadvantages, such as, the constant breakage of picking arms, picking spindles and associated parts, the fact that a shuttle is liable to leave the sley with the possibility of attendant damage to the warp and/or loom and risk of injury to the weaver. Also the constant blows on the shuttle, in many cases, causes the latter to collapse or fracture so that in its passage along the sley it can whip splinters across the warp threads and thus cause considerable damage. Moreover, sudden blows in this manner do not tend to produce a smooth even velocity for the shuttles and the speed obtained is not all that is desired. The construction generally creates considerable noise and vibration with high stresses and strains in the various parts.

The object of this invention is to provide an improved method of and means for applying motion to a loom shuttle.

Accordingly a method of imparting motion to a shuttle consists in the provision of air pressure as the driving force. Moreover, air pressure may be first built up and then released behind the shuttle.

According to a feature of the invention air pressure is directed on to the shuttle rear portion in the shuttle box whilst the shuttle bears against a seating through which the air passes. Also back air pressure created by a shuttle entering a shuttle box may be relieved automatically by valve means. The air inlet to a box may be in alignment with the shuttle or at an angle to its direction of travel. Air compression may be created by one or more pistons (or their equivalent) or obtained from a constant pressure supply source, and the compressed air controlled automatically by valve means to drive the shuttle in each direction across a loom. The said valve means may be displaceable by back air pressure when a shuttle enters a box to admit air back into the compression system.

Referring now to the accompanying drawings in which embodiments of the invention are shown by way of example only:

Fig. 1 is a general front elevation of the

2

"going part" of a loom fitted with single shuttle boxes and air pressure means;

Fig. 2 is a part front elevation of one end of the "going part" with double shuttle boxes;

5 Fig. 3 is a side elevation of the valve timing means;

Fig. 4 is a front elevation of a drop box construction incorporating six shuttle boxes;

10 Fig. 5 is an end view of a rotary box construction;

Fig. 6 is a plan view of a modified shuttle box construction;

Fig. 7 is a sectional plan view of a single box

15 with a modified air inlet.

One embodiment of the invention will now be described in simple form for a single shuttle type of loom (plain looms), i. e., a single shuttle box 1 at each end of the sley board 2 and secured to the bracket 3 at the upper end of the sword 4. As shown, the reed 5 is supported by the brackets 3 immediately behind the sley board and the "going part" is operated by the usual forwardly extending arms connected to the swords and mounted on the crank shaft 6 supported by the loom frame 7 and driven in known manner. The general construction and operation of the "going part" can be according to known arrangements and does not form part of this invention which concerns the shuttle boxes and shuttle driving force.

30 Each shuttle box 1 is of square tubular formation open at its inner exit end (the front and rear walls and top may be flared out slightly to facilitate the entry of a shuttle) and closed at its outer end. A union 8 is secured in the centre of the outer wall to provide an air inlet and an air pipe 9 links the union to the chamber 10 of a control valve 11 which is operated by a solenoid 12 and returned by a spring 13 against an adjustable stop 13a as more particularly shown in Figs. 2 and 5. The valve is adjusted to just close the valve opening. The valve chambers are connected by pipes 14 to compression cylinders 15 secured to the swords and connected together by a compensator pipe 16. A piston 17 (say of the leather washer type) is mounted in each cylinder with its rod 18 anchored to a lever 19 secured on a cross shaft 20 which is oscillated by a lever 21 through connecting rod 22 and strap 23 mounted on an eccentric 24 secured on the crank shaft 6. The solenoids 12 are wired through connections 25, 26 to a timing device comprising contacts 27, 28 which are engaged alternately by a movable selector switch 29 which in turn is wired by connection 30 to a movable

contact 31 adapted to engage a contact 32 which is wired by connection 33 to the mains through a transformer, or to some other power source. As only a low power is required, say, 24 volts, 5 amps., the circuit is completed by grounding through the loom frame. The timing device is more particularly shown in Fig. 3 wherein the selector switch 29, between the contacts 27, 28, is connected by a rod 34 to a bellcrank lever 35 mounted on a spindle 36 and rocked by a cam 37 secured on a higher spindle 38. A second cam 39 on spindle 36 moves the contact 31 into engagement with contact 32 and the gap may be adjusted by device 40. The spindles are geared together by gear wheels 41, 42 with a two to one reduction so that the contacts 31, 32 close for every movement of the switch 29 which has alternate engagements. The spindle 36 is driven through chain wheel 43 and chain 44 from the crank shaft 6.

The operation is as follows: as the crank shaft rotates it not only moves the going part but operates the pistons 17 to compress air in cylinders 15, pipes 14 and 16 and valve chambers 10. When the pistons are almost at the top of their stroke one of the valves 11 (say the left hand valve in Fig. 1) is withdrawn by its solenoid 12 by the contacts 31, 32 being closed and the selector switch 29 engaging the contact 27. Thus compressed air is admitted to the left hand shuttle box 1 behind the shuttle as the pistons are completing their stroke to ensure the shuttle receives the necessary impetus to fly quickly across the sley board into the opposite shuttle box. The going part continues its motion, forwardly then rearwardly again when the right hand valve is opened through contact 28 for compressed air to blow the shuttle back across the sley board and these operations continue with the shuttle being blown first from one box and then the other. The speed of the shuttle is such that it can fly across the sley board when the cranks are back centre and the "shed" is thus open to its fullest extent as distinct from the known picking arm motion which, due to lack of speed, throws the shuttle through the shed before it is fully opened, thus having to force the warp threads apart. Furthermore, the air driven shuttle has a true flight so that it only brushes lightly against the reed with the minimum of frictional resistance, whereas in the old method the shuttle bears hard against the reed so that not only is its flight impeded but the reed wires are worn away rapidly. As the shuttle enters a shuttle box it forces air back through the pipe 9 and as the valve 11 is adjustable in stroke for controlling the air pressure by being spring loaded against an adjustable stop 13a, it is displaced sufficiently to enable the back pressure to be relieved and air to pass back into the compression system. Alternatively, back pressure could be relieved by an exhaust valve at the rear of a box 1, or in pipe 9, in which case the cylinders would have air inlets in known manner. A leather or other check washer 45 is provided at the rear of each box to act as a cushion for the shuttle although the speed of the shuttle is absorbed by the air in the shuttle box as the shuttle compresses it so that an air cushioning effect is created. With the above arrangement air is injected through the washer which forms an air tight seating momentarily for the shuttle to ensure maximum force being obtained from the air pressure.

As shown in Fig. 2, each valve chamber 10 includes a cylindrical stop 13b adjustable axially 75

within the opening through solenoid 12 by means of a set screw 13c to adjust the lower abutment of spring 13 and thereby adjust the back air cushion pressure on the shuttle at which the valve 11 will open to permit air to be forced back through the valve into the air compression system as the piston 17 in compressor 15 is rising. In operation, set screw 13c is set to such position that the momentum of the returning shuttle is entirely absorbed by the air cushion in the shuttle box, preferably the adjustment being made such that the shuttle when filled with the weft is brought to a stop just short of actual contact with the wall of the check washer 45 thereby insuring maximum pneumatic shuttle propulsion force when the shuttle is full. The washer 45 also acts as a cushion to prevent damage to the shuttle in the event that the air valve is maladjusted or a fault develops. Since the return movement of the shuttle into the shuttle box is arrested entirely by the back pressure built up by the shuttle upon entering the shuttle box, any tendency on the part of the shuttle to rebound is eliminated. This is highly important since any rebound of the shuttle will cause the trailing weft to slacken and be of less tension than the other threads, and the finished cloth will show a mark at the place where the tension was lessened.

Use of an air cushion built up by compression 30 of air by the returning shuttle upon entering the shuttle box has the further advantage that as the weft decreases and effects a corresponding decrease in the mass of the shuttle, the shuttle velocity will nevertheless remain constant because 35 of the fact that whilst the pressure at the outlet of compressor 15 remains substantially constant, the shuttle penetrates the shuttle box a less distance as its mass decreases and thus the effective air pressure is not as great.

Whilst the air compressing and control means 40 remain the same, the shuttle box construction may be modified to suit different types of looms. For example, some looms are of the multi-shuttle box type and then the boxes are one unit or connected together and mounted in guides for drop boxes or on an axis for the rotary type. In Fig. 2, two boxes 1^a are mounted in guides 46 and operated by the usual mechanism to register with the union 8 and sley board. Fig. 4 shows six boxes 1^a mounted in guides 46' to be operated in known manner to register with the union 8 and sley board. Fig. 5 shows six boxes 1^a rotatable about an axis 47 on carrier means 48 in known manner for a selected box to register with the sley board and the union 8 which admits air.

In another embodiment of the invention shown in Fig. 6, each shuttle box 1^a at each end of the sley mounted in guides 46a is constructed to have a fixed back plate, top and bottom and outer end with an open inner end and a movable front plate 49. The movable front plate is normally held by a retaining spring 50 so that a shuttle in the box is held more or less lightly but firmly in position whilst the front plate is capable of slight movement against resilient pressure. In this manner, a shuttle is held firmly until it leaves the box but prior to the application of a driving force the grip is slightly resilient. This arrangement aids the shuttle to start with a true flight. The inner face of the movable plate may be covered with material 51 which serves to seal the joints and grip the shuttle but could be dispensed with. The plate is movable about a hinge 52 at the outer end of the box.

For some types of looms the driving force for

the shuttle of compressed air may be admitted through an inlet 8' (or inlets) in the back plate as shown in Fig. 7, to strike the rear side face of a shuttle in the box 14 at an angle (other than a right angle) to the longitudinal centre of the shuttle. In this way the rear of the shuttle is thrust towards the front box plate which can be fixed as shown, or adapted to give slightly as the shuttle is driven out of the box, whereby the nose of the shuttle tends to be thrust towards the inner wall (i. e., the reed 5) of the sley to counteract any tendency to fly outwardly and a true flight is obtained.

The compressed air may be provided from any other convenient source, such as a constant pressure supply source (a back pressure exhaust valve would then be required), instead of being supplied from compression means on the "going part" of the loom or otherwise modified. For example, one compression cylinder could be used but with two, one balances the other and ensures compressed air for either side. The air inlet 8 may be controllable by valve means to adjust the air pressure or speed of entry. Also, the air admission valves 11 could be operated mechanically instead of electrically.

With this method, air bearing a certain amount of moisture can be blown around the warp to have a beneficial effect thereon and the tapered shuttle end divides the following air to spread it. The above constructions may be modified in a variety of ways without departing from the scope of the invention which affords a truer and faster flight for a shuttle in all types of looms and removes all the aforesaid disadvantages of the picking motion.

What I claim is:

1. Picking apparatus for driving a loom shuttle back and forth across a sley board comprising, a tubular shuttle box at each side of the sley board adapted to snugly receive the shuttle, a source of compressed air, means including alternately actuated valves for delivering compressed air alternately to the shuttle boxes to directly propel the shuttle back and forth, and back air pressure relieving means associated with each shuttle box, each such means being adjustable to thereby vary the arresting effect of the air cushion built up in each shuttle box by back air pressure upon a return of the shuttle to the box.

2. Picking apparatus for driving a loom shuttle across a sley board comprising, a tubular shuttle box at each side of the sley board adapted to snugly receive the shuttle, a source of compressed air, a pipe between each shuttle box and air source to deliver compressed air to the rear of said shuttle boxes for direct propulsion of the shuttle back and forth across the sley board, a valve in each said pipe loaded to closed position, said valves being alternately opened to admit compressed air alternately to the shuttle boxes and alternately opened under back air pressure established upon a return of the shuttle to the shuttle box, and means for adjusting the loading on each of said valves to thereby provide regulation of the air cushion in the shuttle box by

which motion of the returning shuttle is arrested.

3. Picking apparatus as defined in claim 2 wherein each of said valves is solenoid actuated and the valve solenoids are alternately energized from a source of current through an adjustable contactor device driven by the loom.

4. Picking apparatus as defined in claim 2 wherein each of said valves is comprised of a spring loaded solenoid plunger, the valve solenoids are alternately energized from a source of current through an adjustable contactor device driven by the loom, and further including means for adjusting the position of the valve plunger relative to the valve ports.

15. 5. Picking apparatus for driving a loom shuttle across a sley board comprising, a tubular shuttle box at each side of the sley board adapted to snugly receive the shuttle, an air compressor associated with each shuttle box, pipe means between the outlet of each compressor and its associated shuttle box, a solenoid actuated valve in each pipe, each of said valves being loaded to a normally closed position and openable either upon energization of the solenoid or upon a rise in back pressure, in the shuttle box and pipe upon return of the shuttle, a contactor device driven by the loom for alternately connecting the valve solenoids to a source of current to deliver compressed air to first one shuttle box and then the other to propel the shuttle back and forth across the sley board, means for adjusting the contact setting of said contactor device to adjust the timing of said valves, and means for adjusting the loading of each valve to thereby provide an adjustable air cushion for arresting motion of the shuttle upon entering each shuttle box.

20. 6. Picking apparatus as defined in claim 5 wherein each air compressor is of the piston-cylinder type, and said valves are timed to open slightly in advance of the end of the compression stroke of the piston to admit pressure air to the shuttle boxes.

JOHN HEATON.
